UNITED STATES PATENT OFFICE.

EDWARD WALSH, JR., OF ST. LOUIS, MISSOURI.

REGENERATIVE KILN.

SPECIFICATION forming part of Letters Patent No. 503,729, dated August 22, 1893.

Application filed May 3, 1892. Serial No. 431,674. (No model.)

To all whom it may concern:

Be it known that I, EDWARD WALSH, Jr., a citizen of the United States, residing in the city of St. Louis and State of Missouri, have 5 invented certain new and useful Improvements in Regenerative Kilns, of which the following is a full, clear, and exact description.

My invention relates to improvements in 10 the general construction and design of kilns for burning bricks and similar articles and materials, and for annealing purposes: and has for its object the convenient and economical use of gas for such purposes; an efficient 15 means for directing the gas and air to the desired part of the kiln, or rather the desired kiln in a battery of kilns; means for promoting a thorough combustion; means for evenly distributing the heat throughout the kiln; 20 convenient means for directing the draft from a kiln that is being fired to another kiln in the battery, thereby making use of the otherwise wasted heat carried off by the products of combustion to heat another kiln; means 25 whereby air to a kiln that is being fired can be first heated by being passed through the material, as burned bricks, that has already been fired and burned in another kiln; means for admitting and regulating a supply of fresh 30 air to the draft from a kiln that is being fired before the same is directed through another kiln.

My invention consists in the details of improvement in construction in kilns for the 35 purposes specified, whereby these desirable results are more effectively and practically carried on, as hereinafter described.

In the accompanying drawings, in which like 40 numerals and letters of reference denote like parts in the several figures, Figure 1 is a side elevation of a battery of kilns built according to my improved form of construction, being partly in vertical section, taken as on the line 1-1 in Fig. 2. Fig. 2 is a plan view of the 45 same, partly in section, taken as on the line 2-2 in Fig. 1. Fig. 3 is a vertical cross-section taken on the line 3-3 in Fig. 2. Fig. 4 is a sectional view taken as on the line 4-4 in Figs. 2 and 3. Fig. 5 is an enlarged plan view 50 of the arrangement of the floor tiles of the kiln. Fig. 6 is a side elevation of one line of the same. Fig. 7 is a side elevation of the

brick checker work of which the cross floor-tile-supporting walls are composed; and Fig. 8 is a vertical section of the same taken as 55 on the line 8-8 in Fig. 7.

The general plan of the arrangement for conducting and regulating the flow of the gas to the different kilns is shown in Figs. 1, 2, and 3, in which [Fig. 2] 1 is the main gas flue, 60 one end of which is connected with the gas producers, or other source from which gas may be obtained, and the other closed. This flue extends the full length of the battery and is directly connected with branch flues 2 65 which lead to flues 3, built in the masonry work of the kilns, extending transversely across the width of the tier of kilns, one along each side of each kiln. The flow of the gas to the flues 3 is controlled and regulated by gas valves 4, placed at some convenient position exterior of the kilns. See Figs. 2 and 3. Extending from the flues 3 in a vertical direction, are formed, in the side walls of the kilns, the flues 5 which extend to and 70 terminate in the ports 6 in the sides of the kilns immediately, or approximately so, below the roof of the kilns. In the side walls of the flues 3, at a point between the valves and the kilns, are formed one or more air induction ports 7 [with proper valves or other means for controlling the same] for admitting air along with the gas, when the kiln is first fired.

On the opposite side of the tier of kilns from 85 where the gas main is situated, is placed the main draft flue 8, which is preferably connected at both ends with a stack [not shown]. This main draft flue is directly connected, at 90 each kiln, with the branch draft flues 9 which connect the same with the large hollow space [shown in Fig. 1] beneath the floor-tiles in the kilns, as shown in Fig. 3. The passage-way through the flues 9 may, in each instance, be closed by vertically movable damper plates 10. 95

Situated immediately below the flues 9 and extending the length of the kilns and to a convenient distance beyond the main draft flue, are the air flues 11. The flues 11 are, in each kiln, connected by the inclined cross flues 12, 100 [see kiln A, Fig. 1 and kilns A and B, Fig. 2] with the vertical air flues 13, similar to the vertical gas flues 5, which terminate in the air ports 14 under the roof of the kilns, at

either side of the same. The wells 15 [see Fig. 3], which form the outer end of the air flues 11, connect directly with the main draft flue 8 and communication therethrough is controlled and regulated by adjustable gate plates 16. The upper end of the wells 15, which are virtually the outer ends of the air flues 11, are closed by adjustable registers 17.

In the main draft flue, at the corners formed by the offsets in the side walls of the same leading to the wells 15 and the flues 9, are formed vertical slide-ways for the removable diagonal gate plates 18.

There is left, in each kiln, in the construction of the same, below the desired floor level, a large ventilation space, as shown in Fig. 1. The floor is supported on the top of the cross walls 20, which, as illustrated in Fig. 1 and, in detail, in Figs. 7 and 8, consist of checker work, in order to provide a free and open draft or ventilation equally from all parts of the floor of the kiln.

As illustrated in Figs. 5 and 6, the floor is made open all over and is formed by placing spanning tiles 19 on edge from one cross wall 20 to the next and in interposing between consecutive tiles the short spacing tiles 21.

The principles of operation of my improved furnace are as follows: Gas is fed to the kiln, as a whole, through the main 1. The gas to each kiln, and to each side of each kiln, is individually and separately regulated by the gas valves 4. The gas is conducted by the flues 3, up through the vertical flues 5 and into the interior of the kilns through the ports 6 under the roof along each side. At the same time, air, in the proper quantity for complete combustion and the proper temperature, as regulated by the air registers 17, is being fed, through the air flues 11, cross flues 12, vertical flues 13 and air ports 14, to the same part of the kiln as the gas, where combustion takes place. In this manner the kiln is made reverberatory, the heat being reflected down from all parts of the heated roof. The products of combustion then traverse the interior of the kiln and flow through the open floor of the kiln, and, from the part of the kiln farthest from the draft flue 8 through the open checker-work wall 20, to the flue 9, and thence to the stack, through the main draft flue 8. In this manner the combustion takes place in all parts of the upper part of the kiln, and, there being no particular part of the floor which is more open than another, the draft is generally distributed and the heat evenly diffused throughout the kiln. This description would apply when a single kiln is being used independently of the rest, as, for instance, when the first is being fired. In this instance, the gates 10 and 16, at the kilns [as E and F] between the kiln being fired [as D, Fig. 2] and the stack, are closed, and the deflection diagonal gate 18 properly placed to direct the draft to the stack, as indicated by the arrow 50 in Fig. 2.

When, for any reason, it is desired to con-

duct the products of combustion of a kiln [as C, Fig. 2] through any other kiln [as B], the deflection gate 18 of the first kiln [C] is turned 70 to deflect the current of heated air in the direction of the desired kiln [B] and the deflection gate 18 at the latter kiln set so as to obstruct the passage through the main draft flue 8 and turn it down the well 15, into the 75 air flue 11 of that kiln, as shown by the arrow 51, in Fig. 2. At the same time, fresh air can be fed, through the register 17 at the latter kiln, to the current of heated products from the former kiln, in order, for instance, 80 to thoroughly consume any unconsumed gas from the first kiln.

The form of construction and of consequent adaptability just described may be taken advantage of in another way; when the material in any one kiln [as C] has been burned, it may be used to regenerate the air fed to another kiln [as B] in which the material is being burned. In this instance, instead of feeding fresh air to the latter kiln [as B] 90 through its own register 17, that register is closed and the register at the former kiln [C] is opened and the air passing down through the heated material contained in the kiln becomes heated before it reaches the latter 95 kiln [B], through the draft flue 9 and that portion of the main flue 8 between the two kilns, the deflection gates 18 being arranged, as indicated in Fig. 2, at the former kiln [C], to direct the draft to the latter kiln and, at 100 the latter kiln [B] to deflect the current of heated air from the main flue 8 down the well 15 thereat, as indicated by the arrow 51.

The method of manipulation, as just described, is of great advantage, and of particular value, in consequent results, when the kiln is used for annealing purposes, when the gradual reduction of temperature is the feature of importance.

The extreme flexibility of manipulation in 110 controlling the absolute and relative amounts of gas and air fed to any one kiln when used singly; this feature, in relation to the admission of air to each kiln independently of the others, when the kilns are worked on the 115 regenerative plan; causing the combustion to take place in the top part of the kiln and the out-draft through the floor of the same, thereby causing an exceedingly even dissemination of the consequent heat throughout 120 all parts of the kiln and about the material being treated therein; making the floor of the kiln of tiles spaced apart and the supporting walls of checker brick-work, whereby the last-mentioned desirable result is facilitated, in that the out-draft is not in the least directed to any particular part of the floor; in providing means whereby the products of 125 any one kiln may be deflected from the main draft flue to the air flue of another kiln, and in the additional provision, in this connection for adjustably feeding fresh air to the 130 said products of combustion, are among the features of improvement and advantage. My

new form of construction—putting the kiln, as a whole, practically under control and making the same an operative kiln, both regenerative and reverberatory.

5 I claim—

1. The herein described permanent floor for kilns, consisting of floor tiles having spacing tiles therebetween of less thickness than the floor tiles proper, substantially as described.
- 10 2. The herein described permanent floor for kilns, consisting of floor tiles having spacing tiles of less length and thickness arranged between, and at the contiguous ends of the floor tiles proper, and supporting walls for the same consisting of open checker brick work, substantially as described.
- 15 3. In a battery of kilns, the combination with the gas and air induction ports leading to the upper part of each kiln, individual draft flues leading from each of said kilns to a common draft flue, an air induction flue leading to each of said kilns, a communicating flue between the main draft flue and the individual air induction flues, and means for controlling the passage between the said main draft flue and the individual air induction flues, and the main draft flues and the individual draft flues, substantially as described.
- 20 4. In a battery kiln, the combination with a gas supply flue and branch pipes leading therefrom to each side of individual kilns, of a conduction flue for the products of combustion leading from each kiln to a main draft flue, and deflection gates at the junction of the main draft flue, and the individual draft flues, for permitting the products of combustion to pass out the main draft flue, or direct them into the next kiln, substantially as described.
- 25 5. In a battery of kilns, the combination

with the main draft flue 8 and deflection gates 18, of air flues 11, registers 17, wells 15 and draft tubes 9; substantially as and for the purposes described.

6. In a battery of regenerative kilns, the combination of individual gas and air flues leading to both sides of said kilns, an open checker work floor, an out-draft flue leading from below the floor of said kilns to a common draft flue, a communicating flue between 50 said main draft flue and said air flues, and removable and adjustable gate plates, adapted to direct the draft from the main draft flue to an individual air flue, all combined and operating in the manner and for the purposes 55 specified.

7. In a battery of regenerative kilns, the combination of individual gas and air flues leading to both sides of said kilns, an open checker-work floor, an out-draft leading from 60 below the floor of said kilns to a common draft flue, a communicating flue between said main draft flue and said air flues, removable and adjustable gate plates, adapted to obstruct the continuous passage-way through 65 said main flue and to deflect the draft from said main flue to said air flues, and gate plates to obstruct communication between said individual draft flues and the main draft flue and to close communication between said 70 main flue and said individual air flues, all combined and operating in the manner and for the purposes specified.

In testimony whereof I have affixed my signature, in presence of two witnesses, this 23d 75 day of April, 1892.

EDWARD WALSH, JR.
